(57) **CLAIM**

The ornamental design for an exercise device, as shown and described.

DESCRIPTION

FIG. 1 is a perspective view of an exercise showing the design;

FIG. 2 is a front elevation view of the exercise device;

FIG. 3 is a top elevation view of the exercise device, and the

opposite bottom view is a mirror image thereof;

FIG. 4 is a rear elevation view of the exercise device; and,

FIG. 5 is a side elevation view of the exercise device, and the

opposite side view is a mirror image thereof.

The broken lines shown in the figures represent portions of

the exercise device that form no part of the claimed design.
